CHAIR BASE OR SIMILAR ARTICLE

Pehr J. Anderson, St. Charles, Ill., assignor to All-Steel Equipment Inc., Aurora, Ill., a corporation of Illinois

Filed July 5, 1960, Ser. No. 61,239

Term of patent 14 years

(Cl. D15—1)

FIGURE 1 is a perspective view of a chair base or similar article, showing my new design;

FIGURE 2 is a plan view thereof;

FIGURE 3 is a side elevational view; and

FIGURES 4 and 5 are sectional views taken along the lines 4—4 and 5—5, respectively, of FIGURE 3.

The dominant features of the design reside in the angular, cross-sectional shaping of the legs of the base, the substantially flat bottom contour of the base characterized particularly by the absence of a downwardly projecting spindle, and the relatively high and narrow, substantially cylindrical, upstanding hub portion of the base, all as shown.

I claim:

The ornamental design for a chair base or similar article, substantially as shown and described.
